UNITED STATES PATENT OFFICE.

GEORGE A. SHIELDS, OF COLUMBUS, OHIO.

ANNEALING OVEN OR LEER.

1,177,061.

Specification of Letters Patent. Patented Mar. 28, 1916.

Application filed October 26, 1914. Serial No. 868,674.

To all whom it may concern:

Be it known that I, GEORGE A. SHIELDS, a citizen of the United States of America, residing at Columbus, in the county of Franklin and State of Ohio, have invented certain new and useful Improvements in Annealing Ovens or Leers, of which the following is a specification.

The present invention relates to improvements in annealing ovens or leers, and is especially adapted for use in connection with large plate glass, although of course it is adapted for use with any other kind of glassware that is to be slowly passed through the annealing oven for the purpose of tempering and cooling.

The primary object of the invention is the provision of means by which the glass plates or pieces may be continuously passed through the oven so that they will be properly annealed during their passage therethrough, and this movement is accomplished by a step by step action imparted to the plates.

The invention consists essentially in the combination and arrangement within the annealing oven of two members, one capable of a longitudinal movement and the other member vertically movable, and both elements adapted to return to their normal positions at the end of a working action.

In the accompanying drawings I have illustrated a complete example of the physical embodiment of my invention constructed according to the best mode I have so far devised for the application of the principles of my invention.

Figure 1 shows an annealing furnace or oven in section, with my conveyer device illustrated therein, in connection with a flattening stone or wheel for cylinder glass, the conveyer being in normal position. Fig. 2 shows a portion of Fig. 1 with the conveyer in operative position. Fig. 3 shows a vertical sectional view of the annealing furnace or oven with my conveying device in side elevation and normal position. Fig. 4 is a view similar to Fig. 3 with the conveyer in operative position. Fig. 5 is a detail sectional view, showing in side elevation, the supports for the longitudinally and vertically movable members of the conveyer. Fig. 6 is an end view of Fig. 5 showing a

portion of the oven wall, a rock bar and connections outside the wall for rocking the 55 bar to impart the vertical movement to the vertically movable member. Fig. 7 is a top plan view of Fig. 6, the operating link for the rock bars being omitted. Fig. 8 is a view similar to Fig. 5 with the rock bar 60 raised and the vertically movable member of the conveyer lifted.

In the preferred embodiment of my invention I have illustrated its use in connection with a well known type of furnace or oven 65 as 1 to which the glassware to be annealed is introduced through the stock hole 2 of the furnace wall. It will be understood that the stock from which the glass plates are to be made is brought to the furnace from the 70 glass making machine in the form of a cylinder for each plate, and the cylinders are laid upon the rotary flattening stone or wheel 3 at approximately the point marked 4, and as the wheel revolves in the direction 75 of the arrow, the cylinder is flattened into a plate ready for annealing. From the point marked 5 in Fig. 1, the plates are removed and placed upon the heated end of the annealing conveyer in the oven 6. 80

In Fig. 1 it will be understood that the left end of the oven is the heated end and the right end is the cooler end, and that the glass plates are to pass through the oven from left to right, thus undergoing the process of heating and then gradually cooling for the purpose of removing brittleness or increasing ductility, as readily understood by those skilled in the art. 85

There are two co-acting elements to the 90 conveyer, one the longitudinally movable carrier 7, and the other, the vertically movable lifting device or elevator 8. The carrier 7 comprises a plurality of rods 7' arranged in parallelism in a horizontal plane, 95 and joined at one end by the cross rod 9 and couplings 10, so that the rods 7' form a unitary structure, and this structure is capable of supporting a multiplicity of glass plates, and in conjunction with the other member 100 8, moving them step by step to the right in Fig. 1. The member 8 of the conveyer also comprises a series of metal rods, as 8', arranged in parallelism and extending from end to end of the oven 6. These rods are 105 shorter than the rods 7', and in Fig. 5 par-

ticularly it will be seen that the rods 7' are above the rods 8' when the device is in normal position, but in Fig. 8 it will be apparent that rods of the member 8 may be 5 lifted above the rods of the member 7.

- The member 7 of the conveyer, or rather its rods 7' are each supported on a roller or series of rollers as 11. There are five rods 7' illustrated in the drawings, and each rod 10 is supported by four rollers. The number of rods and rollers used may, of course, be increased or diminished as desired. Each of the rollers forms one of a series of five that are supported by means of an angle bar 15 or bracket 12, preferably of angle iron and extended across the oven 6 and supported from a lug 13 projecting upwardly from a base plate 14 located in a slot 15 in the side walls of the oven. Each roller is directly 20 supported from the angle iron by means of a pair of arms 16, 16, undercut or grooved at 17 for the accommodation of the pintle or trunnion 18 of the roller. The pintles or trunnions are free to roll from one end of 25 the groove to the other end as will be described. These arms 16 are fixed above the apex of the angle iron by means of a plate 19 at the base of the angle iron, and a pair of bolts 20, one at each side of the angle iron. 30 In Fig. 7 it will be seen that these arms are the bifurcated or forked end of the plate 21 through which the bolts 20 pass, and by which the plate and its arms are rigidly fixed to the angle iron. From this construction 35 it will be obvious that the carrier 7 of the conveyer, which has its rods 7' supported in the rollers 11, may be moved longitudinally a distance in proportion to the travel of the trunnion 18 in the groove 17 40 in the arms 16, and when so moved, the rollers will revolve on their trunnions which travel from end to end of the groove.

In the plan views of the drawings it is clear that the rods 7' and rods 8' are arranged alternately across the oven, but the rods 8' do not move longitudinally thereof. The rods 8' instead of being supported in rollers are supported in a series of rock arms 22, and pivoted to the extreme right, Fig. 4, 45 each of which, excepting the arm to the right, is bifurcated or forked at its end 23 and rounded to neatly fit under the rod. These rock arms are rigidly attached by a plate 24 and bolts 25 to an angle iron rock 50 bar 26, the end of the rock arms being formed to straddle over the angle iron as clearly shown in Figs. 5 and 8. The rock bars 26 are arranged, one adjacent each of the angle iron bars 12, to extend across the 55 oven, and each rock bar is supported at its ends upon a fulcrum lug 27 that rises from the end of the base plate 14 that supports the stationary cross bars 12. These pairs of lugs are triangular in cross section and their 60 apices form knife edge supports for the rock 65

bar which is supported thereon so that the bar may rock on the lugs as a fulcrum, and when so rocked the arms 22 will lift the elevating member of the conveyer above the carrier member.

The rock bars are actuated from outside the oven by means of a link 28 to which the levers 29 are pivoted and these levers are fixed, one to each of the rock bars, so that when the link is pulled to the right in Fig. 75 5, this movement will raise each rock arm 22 and elevate all of the rods 8'. If desired small metallic clips 30, Figs. 6 and 7, may be employed to prevent lateral movement of the cross angle irons. These cleats may be 80 adjusted on the angle irons by means of the bolt 31 and the slots 32 in the cleats, as will be readily apparent.

The *modus operandi* of the device is as follows: A plate of glass is placed upon the 85 left end of the carrier 7 while the carrier is at its extreme left position. The carrier is then pulled to the right, the rods 7' passing over the rollers 11 and the trunnions of the rollers traveling over the grooved arms as 90 described. When the carrier reaches its extreme right position its movement is stopped and the carrier with the plate on it is at rest. The link 28 is now pulled to the right and this action causes the rock bar to rock 95 and swing the rock arms of the elevator supports upwardly carrying with them the rods 8' of the elevator 8. The elevator is lifted above the carrier and it lifts the glass plate from the carrier as it passes the latter. Now 100 while the elevator is raised the carrier is returned to the left free of the glass plate, leaving the plate at rest upon the raised elevator. The elevator is then depressed and as its rods 8' pass the rods 7' the glass plate 105 is again deposited on the carrier, but at a position to the right of the original position occupied by the plate when it was first placed upon the carrier. Additional plates of glass are successively placed upon the left 110 end of the carrier, and with each additional plate the above described operation is undergone so that the first plate for instance, is moved step by step with the other plates following, until it has slowly traversed the 115 length of the annealing oven and may be taken from the carrier at the right end of the oven. After the conveyer has become filled with glass plates it will be seen that the plates are fed to the conveyer at the left 120 end and delivered at the right end of the conveyer in continuous order. During the passage of the glass plates from the heated left end to the comparatively cooler right end of the oven, the glass is annealed, and the annealing may be governed by the length of the oven, or the speed of the moving parts of the conveyer, and further the movement of the carrier will of course be regulated by the size of the plate that is to 125 130

be annealed, a large plate requiring more extended movement than a smaller plate as is obvious.

What I claim is:—

- 5 The combination in a conveyer with a longitudinally reciprocable carrier composed of spaced parallel rods and supporting rollers and suitable supports for the rollers, of an elevator comprising a set of alternating rods adapted to co-act with the carrier rods, spaced plates with knife edge lugs

thereon, transversely extending angle iron bars fulcrumed on said lugs and formed with arms for supporting said elevator rods, and means for rocking said bars.

15

In testimony whereof I affix my signature in presence of two witnesses.

GEORGE A. SHIELDS.
